Primary Examiner — Kendra Leslie Hamilton

(57) **CLAIM**

The ornamental design for a baby feeder, as shown and described.

DESCRIPTION

FIG. 1 is a top, front, right perspective view of a baby feeder showing my new design;

FIG. 2 is a bottom, rear, left perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a top, front, right perspective view of the baby feeder, shown exploded for clarity of disclosure;

FIG. 10 is a bottom, rear, left perspective view of the baby feeder, shown exploded for clarity of disclosure;

FIG. 11 is a bottom, rear, left perspective view of the baby feeder, shown in a secondary condition of use; and,

FIG. 12 is a bottom, rear, left perspective view of the baby feeder, shown in a tertiary condition of use.

The broken lines shown in the figures depict portions of the baby feeder that form no part of the claimed design.

1 Claim, 12 Drawing Sheets
